FREDERIC BILLON, OF SOLOTHURN, SWITZERLAND.

ELECTRIC IGNITION APPARATUS.

Application filed July 8, 1918. Serial No. 243,893.

To all whom it may concern:

Be it known that I, FREDERIC BILLON, a citizen of the Swiss Republic, residing at No. 534 St. Niklausstrasse, in Solothurn, Switzerland, have invented certain new and useful Improvements in Electric Ignition Apparatus, of which the following is a specification.

In stationary coil ignition apparatus of the type in which the induction coil is stationary, and the inducing magnet rotates it is usual to employ rotary cam discs and stationary interrupter levers as the mechanism for interrupting the primary circuit. In such apparatus, however, wherein it is desired to provide a means of adjustment of the point of ignition by hand, it is necessary that the interrupter levers shall be capable of being displaced by the desired angle of variation of the point of ignition. This capability of displacement of the interrupter levers necessitates that the leads to the two interrupter contacts shall either be made flexible, or that rubbing contacts shall be employed for that purpose. Both constructions, however, entail an increase in the primary resistance of the ignition apparatus, which, as is well known, should be kept as low as possible.

The improved apparatus forming the subject-matter of the present invention allows of obviating that drawback. The improved apparatus consists in the feature that an intermediate member is arranged so as to be capable of rocking on its axis in such a manner that its displacement takes place along an arc of a circle concentric to the said axis. The result of this is that the limiting surface of the rotating cam strikes the intermediate member always at the same angle and independently of the position of the said intermediate member, and that the force that effects the raising of the intermediate member remains the same in direction and amount for each variation.

In the accompanying diagrammatic drawings:—

Figure 1 shows an elevation, and

Figure 2 a longitudinal section of a construction wherein the intermediate member and the interrupter lever are rotated in a plane at right angles to the axis of the apparatus.

Figures 3 and 4 illustrate a construction wherein the intermediate member and the

interrupter levers move in planes at right angles to each other.

The interruption takes place between the two contacts *a* and *b*, by the fact that the contact *b* is alternately brought into engagement by the spring *e* against the contact *a*, which is insulated from the frame and contact *b* by the insulating piece *s* and the make and break contact is effected by the intermittent action of the bell crank lever *d* being secured upon the pivot pin *c*, the bell crank lever *d* being operated to open and close the contacts by the cam disc *h* connected to the axle of the induction magnet, but this connection does not take place directly but indirectly through the medium of a member *f* that is adapted to rock upon a pivot *g* secured in a projection on the edge of the disc *l*. The member *f* bears with one end *k* on the cam disc *h* while its opposite end engages with the bell crank lever *d*. The intermediate member *f* is carried by a disc *l* which is rotatably mounted in a bearing formed in the frame of the device. The axis of the disc *l* is arranged co-axial with the axis of the rotor of the device, and a handle *i* is fixed to the disc *l* to enable the disc to be displaced through an angle α .

The interruption takes place at the instant when a projection on the cam disc *h* passes underneath the head *k* of the intermediate member *f*. Since the displacement affects solely the intermediate member, which does not carry any current, but only performs a mechanical function, neither flexible leads or rubbing contacts are required.

Various forms of apparatus having the same components differently arranged are shown as examples of construction, which perform the same object and are included in this application to show how such an object may be obtained.

A considerable advantage is gained by arranging the movable interrupter lever to rock in a plane at right angles to the plane in which the intermediate member is displaced, and by widening its end (bearing upon the intermediate member) to correspond with the range of displacement of the intermediate member, so that the length of the effective leverage acting upon the interrupter lever will remain unchanged by the displacement of the intermediate member.

A constructional example of this arrangement is illustrated in Figure 3 in front ele-

vation, and in Figure 4 in section along the axis of the apparatus. The intermediate member *k* which is fixed to the lever arm *f*, and can rock on the pin *g*, is fixed by means 5 of the disc *l* to the handle *i*, and can be displaced together with this handle in the plane of the drawing. The movable interrupter lever *d*, *d'*, which is fulcrumed at *c*, is adapted to rock at right angles to the said 10 plane with its contact *a* that is situated opposite the stationary contact *b* and insulated therefrom by the insulating piece *s*. The arm *d'* of this lever is pressed by the spring *e* upon the intermediate member *k* so long as 15 the contacts *a* and *b* are not pressing upon each other. This arm *d'* carries an enlargement *m* which is constructed at right angles to the plane of oscillation of the lever, and covers the range of displacement of the intermediate member *k*, so that the cam disc *h* 20 serves to operate the interrupter lever with unchanged leverage in all positions of the intermediate member.

Having thus described my invention, what 25 I claim is:—

1. In apparatus for varying the point of ignition in stationary coil electric ignition apparatus comprising in combination a make and break contact device with a spring controlled bell crank pivoted lever, a cam with projections thereon attached to the axle of the induction magnet, a hand operated circular member in an axial line with the said cam and having an extension lever and a 30 projection, and a curved intermediate member carried by said projection, such curved member having a projection on each face thereof, one of the last named projections engaging the cam and the other projection 35 of the curved member engaging said bell crank lever.

2. In apparatus for varying the point of ignition in stationary coil electric ignition apparatus comprising in combination a make and break contact device with a spring controlled double ended lever, a cam with projections thereon attached to the axle of the induction magnet, and a hand operated circular member in an axial line with said 40 cam, having an extension lever with a curved projection engaging the edge of the cam, all mounted in an operative position in an extension of the frame, substantially as described.

3. In mechanism for varying the point of ignition in stationary coil electric ignition apparatus, a stationary contact, a plural armed pivotally mounted lever carrying a movable contact co-operating with the stationary contact for making and breaking 55 a circuit, a rotating cam disc, a controllable member mounted to swing about the axis of the disc, and means carried by and movable with said member having one surface which bears against the cam disc and moves the 60 member in one direction, and another surface which bears against the lever and is operated by said member.

4. A mechanism as defined by claim 3, in which a spring yieldingly presses the movable contact against the stationary contact.

5. In mechanism for varying the point of ignition in stationary coil electric ignition apparatus, a stationary contact member, a plural armed pivotally mounted lever having one of its arms carrying a movable contact member which co-operates with the stationary member for making and breaking 75 a circuit, a rotating cam disc, a pivoted member fulcrumed to swing about the axis of 80 the disc, and a lever pivotally mounted upon the pivoted member and having one surface which bears upon the periphery of the disc and is operated by said disc and another surface which engages one of the arms of 85 the first lever and actuates the same.

6. A mechanism as defined in claim 5 in which the fulcrum of the lever pivoted on the pivoted member is movable in an arc having the axis of the disc as a centre.

7. In an apparatus for varying the point of ignition in stationary coil electric ignition apparatus, comprising a rotary cam disc and a movable interrupter lever, an intermediate member situated between said cam disc and said interrupter lever, mounted so as to be capable of rocking in a plane at right angles to the plane of displacement of said intermediate member, and the end of said interrupter lever that bears upon said intermediate member being formed with an enlargement at right angles to its rocking plane equal to the range of displacement of said intermediate member, whereby the length of the effective leverage on said interrupter 100 lever remains unchanged in the displacement of said intermediate member.

FREDERIC BILLION.
